UNITED STATES PATENT OFFICE.

GEORGE HERBERT BURLEIGH, OF JERSEY CITY, NEW JERSEY.

MECHANICAL WASTE.

No. 892,646.

Specification of Letters Patent.

Patented July 7, 1908.

Application filed March 15, 1907. Serial No. 302,584.

To all whom it may concern:

Be it known that I, GEORGE HERBERT BURLEIGH, a citizen of the United States, and a resident of Jersey City, county of Hudson, and State of New Jersey, have invented certain new and useful Improvements in Mechanical Wastes, of which the following is a full, clear, and exact description.

This invention relates more particularly to wastes for bath tubs, basins and the like.

The primary object of the invention is to provide simple and efficient means whereby the water within the tub or receptacle may be held therein from beneath the receptacle; which is so constructed that it will not easily get out of order, and which may be readily cleaned at any time; which provides for a complete, direct and effective discharge of all the water; and which is thoroughly sanitary in its arrangement, so that water or other matter will not collect in any part of the device.

A further object of the invention is to provide simple means whereby the device may be readily applied to the receptacle, and to provide a simple and effective straining or protecting means for the device.

With these and other objects in view, the invention will be more particularly herein-after described with reference to the accompanying drawings, which form a part of this specification, and will then be pointed out in the claims at the end of the description.

In the drawings, Figure 1 is a vertical section, partly broken away, and partly in elevation, of one form of device as applied to a bath tub. Fig. 2 is a sectional plan view taken on the line 2—2 of Fig. 1. Fig. 3 is a detail elevation of the overflow cap. Fig. 4 is a detail plan of a part of the strainer or protector. Fig. 5 is a vertical section taken on the line 5—5 of Fig. 1. Fig. 6 is a section taken on the line 6—6 of Fig. 1; and Fig. 7 is a section taken on the line 7—7 of Fig. 1, showing the drainage opening through the valve seat.

The bath tub or other receptacle 10 may be of the usual or of any desired construction, and in the bottom near one end thereof is a discharge opening 11. The opening 11 may be enlarged for a part of its length, and in the enlarged part of the opening is adapted to fit the flange of a thimble 12 forming a part of a strainer or protector 13. This strainer, device or protector 13 is provided with openings 14 around the periphery

thereof, and in the openings are adapted to fit pins or projecting portions 16 which are secured to or formed as a part of the member or cap-piece 17. These pins may be cast to 60 the cap-piece 17, and the under surface of the openings 14 are enlarged, so that the pins or projections 16 may be spread over and serve as rivets to securely fasten the cap-piece 17 to the thimble or member 12. The 65 cap-piece 17 has a spider-like form and comprises a ring 18 from which project the arms 19 to the under sides of each of which are the rivets or projections 16. As will be seen this forms a very simple device for preventing 70 large particles from entering the thimble or member 12, such as soap, and provides simple means whereby the members may be readily made and united together, thereby serving as a strainer as well as a protecting 75 device.

As a means for holding the body of water within the receptacle, I secure to the thimble 12 a valve casing 20, and between the casing and the body of the receptacle is a gasket or 80 washer 21 for the purpose of making a tight joint. The casing 20 has a threaded opening 22 which is adapted to fit the threaded end of the thimble 12, by which the casing and the device 13 are removably held together. The 85 casing 20 is open at one end, and is provided with a cap 23, and within the casing, and adjacent to the opening 22, is a valve seat 24. The valve seat is in the path of movement of a reciprocating valve 25. This valve 25 has 90 its end beveled to correspond to the bevel of the valve seat, and has two parts or members 26 and 27. The part 27 is cup-shaped, and within said member is arranged a collar or cap-piece 28, between which cap-piece and 95 the inner surface of the member 27 is arranged a spring 29 by which the cap-piece 28 and the valve are yieldingly held together. The member 26 of the valve is cup-shaped and of a smaller diameter than the member 100 27 to permit the waste water at the rear and between the member 26 and the cap 23 to discharge more readily, and the two parts are securely held together, and to the cap or collar 28 is fastened a bolt or rod 30, said member 26 serving to inclose the cap-piece 28 and spring 29 within the member 27 and seal the open end thereof. This rod 30 has its forked 105 end connected to a rod 31, and this latter rod is held to a crank 32, so that as said crank 32 110 is rotated the valve 25 may be reciprocated within the casing 20, to permit the water to

pass from the receptacle 10 through the casing 20 and into and out through the discharge 33. The casing 20 may be made to incline somewhat, and to the rear of the valve 25 is a channel 34 which is formed in an enlarged portion of the casing, and said channel or groove is adapted to communicate with an opening 35 through the valve seat. By this means the water is sustained from beneath the receptacle and practically every particle of water will have access to the discharge 33 when the valve is forced away from its seat, and in this way refuse, grease or other matter will be prevented from collecting within the casing.

The crank 32 for operating the connecting rod 31 and valve 25 is rotatably held in the casing 20. To secure this the crank is provided with a flange 36, which is adapted to rest and be supported upon a bracket 37, which is preferably cast as a part of the casing 20. This bracket 37 has an opening in which is journaled the part 38 of the crank, and said bracket is connected to the casing by means of webs or wings 39, so that the opening 40 to the casing will not be entirely closed. The flange 36 is held against the bracket 37 by means of a ring 41, which is fastened to the bracket 37 and has a flange fitting over the flange 36 of the crank shaft, by which means the said crank is held to rotate within the valve casing 20, and at the same time provides means whereby the crank shaft may be readily inserted within the casing when the parts are assembled. The upper end of the crank is provided with a socket which, as shown, is elliptical, and in the socket is adapted to fit the end of a rod 42, which is secured by a pin 43 to the crank. The lower end of the rod 42 is also elliptical to fit the socket of the crank, and when rotated, as will be presently described, will reciprocate the valve 25 to sustain the water within the receptacle or to permit it to be discharged therefrom as desired.

The opening 40 of the valve casing connects with the pipe 44 forming a part of the overflow, and to provide a tight joint between the valve casing 20 and said pipe is a cap nut 45, and a suitable washer or other packing 46. The pipe 44 may be of any desired length and surrounds the operating rod 42, and at the upper end thereof is held by threads or otherwise to a T-shaped fitting or connection 47. This connection or fitting 47 has its upper end 48 open and extends upward any desired distance, and said fitting is provided with an overflow opening 49 in which is arranged a boss 50. This boss 50 has a threaded opening in which is adapted to fit the end of the screw 51 which holds the open cap-piece 52 and the fitting 47 to the opposite sides of said receptacle, a flange 53 and a gasket or washer 54 being provided to make a tight joint between the receptacle

and the fitting 47. The overflow connection may be of any desired construction, and is intended to prevent the water in the receptacle from rising beyond a predetermined height, the surplus being permitted to discharge directly into the fitting 47 and pipe 44, and from there into the discharge 33.

To operate the rod 42, I provide the upper end thereof with a handle 55 which may be of any desired form, and said rod is caused to pass through an opening in the rim 56 of the tub or receptacle 10. A guide or thimble 57 fits around the rod, and has its lower end screw-threaded, and on said threaded end are lock nuts 58 which hold the thimble on the rim 56. It will be seen that as the handle is moved the rod 42 will rotate the crank 32, and through the crank, the rod 31 will reciprocate the valve 25 within the casing 20.

From the foregoing it will be seen that simple and efficient means is provided whereby the water may be held within the receptacle from beneath the lower surface thereof; which permits a direct discharge of the overflow and of the waste water; which may be readily clamped or taken apart, and in which objectionable matter will not collect, thereby providing a thoroughly sanitary device.

Having thus described my invention, I claim as new and desire to secure by Letters Patent:—

1. A device of the character described, comprising a valve casing having inlet and discharge openings, a strainer secured in the inlet opening, a valve seat arranged in the casing between the discharge and inlet openings, a valve adapted to engage the valve seat, a rod, a spring yieldingly holding the valve to the rod within the casing, a crank arranged within the casing and connected to the rod, a vertically disposed tubular connection fitted to the casing, an overflow connection at the upper end of the tube, a vertically arranged rod connected to the crank and passing through the overflow connection, and means for operating the rod to reciprocate the valve.

2. A device of the character described, comprising a valve casing having inlet and discharge openings, a strainer secured in the inlet opening, a valve seat arranged in the casing between the discharge and inlet openings, a valve adapted to engage the valve seat, a rod, a crank arranged within the casing and connected to the rod, a vertically disposed tubular connection fitted to the casing, an overflow connection at the upper end of the tube, a vertically arranged rod connected to the crank and passing through the overflow connection, and means for operating the rod to reciprocate the valve.

3. A device of the character described comprising a valve casing having inlet and discharge openings, a valve seat arranged in the casing between the discharge and inlet

openings and having a channel therethrough, a valve adapted to engage the valve seat, a rod, a spring yieldingly holding the valve to the rod within the casing, a crank arranged 5 within the casing and connected to the rod, a vertically disposed tubular connection fitted to the casing, an overflow connection at the upper end of the tube, a vertically arranged rod connected to the crank and passing 10 through the overflow connection, and means for operating the rod to reciprocate the valve.

4. A device of the character described, comprising a valve casing having an open end provided with a cap to close the same, an 15 inlet opening adapted to connect with the discharge of a receptacle and located at one side of the casing, a valve seat arranged adjacent to the inlet opening of the casing, a horizontally reciprocating valve arranged in the 20 casing and adapted to engage the valve seat, a discharge opening on the opposite side of the valve seat from the inlet opening and at the lower end of said casing, said casing being provided with an overflow opening above the 25 discharge opening, a crank movably held in the casing over the discharge opening, an overflow connection communicating with the overflow opening of the casing, connections between the valve and the crank whereby 30 the latter may be reciprocated, and a vertically disposed rod passing through the overflow connection and engaging the crank.

5. A device of the character described, comprising a valve casing, having an inlet 35 opening adapted to connect with the discharge of a receptacle and located at one side of the casing, a valve seat arranged adjacent to the inlet opening of the casing, a horizontally reciprocating valve arranged in the casing and adapted to engage the valve seat, a discharge opening on the opposite side of the valve seat from the inlet opening and at the lower opposite end of said casing, said casing being provided with an overflow opening 40 above the discharge opening, a crank movably held in the casing over the discharge opening, an overflow connection communicating with the overflow opening of the casing, connections between the valve and the 45 crank whereby the latter may be reciprocated, a vertically disposed rod passing through the overflow connection and engaging the crank, and a handle on the rod whereby the rod may be reciprocated.

6. A device of the character described, comprising a valve casing having an inlet opening adapted to connect with the discharge of a receptacle and located at one side of the casing, a valve seat arranged adjacent 50 to the inlet opening of the casing, a valve arranged in the casing and adapted to engage the valve seat, a discharge opening on the opposite side of the valve seat from the inlet opening and at the lower end of said casing, 55 said casing being provided with an overflow

opening above the discharge opening, a crank movably held in the casing over the discharge opening, an overflow connection or fitting communicating with the overflow opening of the casing, connections between the valve and the crank whereby the latter may be operated, and a rod passing through the overflow connection and engaging the crank. 73

7. The combination with a valve casing 75 having inlet and discharge openings and provided with a valve seat between said openings, of a substantially cup-shaped valve member adapted to engage the seat, a cap-piece yieldingly held within the valve member, a bolt secured to the cap-piece and passing loosely through the valve member, a second valve member inclosing the cap-piece and held to the open end of the cup-shaped valve member, and means for operating the 85 valve members.

8. The combination with a valve casing having inlet and discharge openings provided with a valve seat between the said openings, of a substantially cup-shaped valve 90 member adapted to engage the seat, a cap-piece located within the valve member, a spring interposed between the cap-piece and the valve member, a bolt secured to the cap-piece and passing loosely through the valve 95 member, and a second cup-shaped valve member inclosing the spring and cap-piece and held to the open end of the cup-shaped valve member, and means for operating the valve members. 100

9. In a device of the character described, the combination with a receptacle having a discharge opening and an overflow opening, of a valve casing communicating with the discharge and the overflow openings of the 105 receptacle and having a discharge opening, a valve seat arranged in the casing between the discharge of the valve casing and the discharge of the receptacle, a valve having two members one smaller than the other 110 connected together one of which is adapted to engage the seat and hold the water in the receptacle, a cap-piece, a spring interposed between one member of the valve and the cap-piece, a rod or bolt connected to the cap-piece, a connecting rod held to the bolt, a crank for operating the rod, and means for operating the crank. 115

10. In a device of the character described, the combination with a receptacle having 120 discharge and overflow openings, of a valve casing communicating with the discharge opening of the receptacle and having a discharge opening in said casing, connections between the discharge and the overflow, a 125 valve seat arranged in the casing between the discharge of the valve casing and the discharge of the receptacle, a valve adapted to engage the seat and hold the water in the receptacle, a cap-piece, a spring interposed 130

- between the valve and the cap-piece, a rod or bolt connected to the cap-piece, a connecting rod held to the bolt, a crank for operating the rod, and means for operating the crank.
- 5 11. In a device of the character described, the combination with a valve casing having inlet and discharge openings and provided with a valve seat between the inlet and discharge openings; a valve adapted to engage the seat, a cap-piece, a rod or bolt connected to the cap-piece, a connecting rod held to the bolt, a crank for operating the rod, and a second rod for operating the crank.
- 10 12. In a device of the character described, the combination with a receptacle provided with discharge and overflow openings, of a horizontally arranged valve casing communicating with the discharge and overflow openings and having a discharge opening in said casing, connections between the discharge and the overflow, a valve seat arranged in the casing between the discharge of the valve casing and the discharge of the receptacle, a reciprocatory valve having two members one smaller than the other connected together one of which is adapted to engage the seat and hold the water in the receptacle, a cap-piece, a spring interposed between one member of the valve and the cap-piece, a rod or bolt connected to the cap-piece, a connecting rod held to the bolt, a crank for operating the rod, and a vertically disposed rod for operating the crank.
- 15 13. A device of the character described comprising a valve casing having inlet and discharge openings, a strainer secured in the inlet opening, a valve seat arranged in the casing between the discharge and inlet openings, a valve having two members one smaller than the other connected together one of which is adapted to engage the seat, a cap-piece, a spring interposed between one member of the valve and the cap-piece, a rod or bolt connected to the cap-piece, a connecting rod held to the bolt, a crank for operating the rod, and a second rod for operating the crank.
- 20 14. The combination with a valve casing having an inlet and a discharge, and a valve seat arranged adjacent to the inlet of the valve casing, of a reciprocatory valve movable within the casing, said casing having a channel therein and an opening through the valve seat for drainage purposes, a rod connected to the valve, a crank journaled in a part of the casing and having a flange thereon, a flanged ring for retaining the crank rotatable within the casing, and a rod for operating the crank.
- 25 15. The combination with a valve casing having inlet and discharge openings, and a valve seat arranged adjacent to the inlet opening, of a reciprocatory valve movable
- 30 within the casing and comprising two members one of which is smaller than the other, 65 said casing having a channel therein and an opening through the valve seat for drainage purposes, a rod yieldingly connected to the valve, a crank journaled in a part of the casing and having a flange thereon, a flanged ring for retaining the crank rotatable within the casing, and a rod for operating the crank.
- 35 16. The combination with a valve casing having inlet and discharge openings, and a valve seat arranged adjacent to the inlet opening, of a reciprocatory valve movable within the casing, said casing having a channel therein and an opening through the valve seat for drainage purposes, a rod yieldingly connected to the valve, a crank journaled in a part of the casing and having a flange thereon, a flanged ring for retaining the crank rotatable within the casing, and means for operating the crank.
- 40 17. The combination with a thimble having a flange thereon provided with openings, of a spider-like cap-piece fitting over the thimble and provided with projecting arms each having an integral projection thereon adapted to fit the openings in the thimble whereby the two parts of the device may be rigidly held together.
- 45 18. The combination with a thimble having a flange thereon provided with openings, of a spider-like cap-piece fitting over the thimble and provided with a central opening projecting arms each having an integral pin thereon adapted to fit the openings in the thimble and adapted to form rivets whereby the two parts of the device may be rigidly held together.
- 50 19. In a device of the character described, the combination with a valve casing and a valve movable therein, of a crank journaled within the casing and operatively connected with the valve, said crank having a flange and an elliptical socket, a flanged ring engaging the flange on the crank and rotatably holding it within the casing, and a rod having an elliptical lower end held within the elliptical socket in the crank for operating the latter.
- 55 20. In a device of the character described, the combination with a valve casing and a valve movable therein, of a crank journaled within the casing and operatively connected with the valve, said crank having a flange, a flanged ring engaging the flange on the crank and rotatably holding it within the casing, and a rod for operating the crank.
